UNITED STATES PATENT OFFICE.

JAMES PATRICK MADDEN, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

SALT PRESS.

Application filed October 12, 1921. Serial No. 507,221.

To all whom it may concern:

Be it known that I, JAMES P. MADDEN, a citizen of the United States, and residing at Bethlehem, Lehigh County, State of Pennsylvania, have invented certain new and useful Improvements in Salt Presses, of which the following is a specification.

This invention relates to presses adapted to compress granular material into solid blocks of the desired shape and size and is especially designed for use in salt presses. It consists in a novel construction relating to the die mechanism, and it may be used in well known forms of presses. It includes a die block adapted to rest on and be secured to the table of a press below the plunger and embodies means in or connected to the die block above its lower end for accurately and easily moving the bottom die member downwardly from the lower end of the die chamber sufficiently to clear the compressed material and then moving it laterally out of the way to permit the ejection of the compressed material from the chamber and then moving the die member back to position under the die chamber, pushing the ejected block of material ahead of it out of the way, and then moving the die member back up against the lower end of the chamber ready for the next compression. The movement to or from operative position is produced by one continuous movement of an operating member and in the particular embodiment of the invention shown, the removal of the die member from operative position takes place when hydraulic power is turned on and the die member remains in its side or inoperative position as long as the source of hydraulic power is connected but when that power is disconnected, the die member automatically returns to operative position and the compressed block is pushed out of the way. The operation being automatic, on the connection or disconnection of the source of power, the attention and care necessary on the part of the operator is reduced to a minimum. The structure is furthermore simple, strong and not likely to get out of order. The novel features will be more fully understood from the following description and claims taken with the accompanying drawings.

In the drawings:

Figure 1 is a vertical section through a

press and through the die mechanism in place on the table of the press.

Figure 2 is a similar view taken on a plane at right angles to that of Figure 1;

Figure 3 is a cross section of the press on a horizontal plane slightly above the supporting table through wedge member 24 looking down; and

Figure 4 is an enlarged section corresponding to that of Figure 1 but showing only the mechanism at the lower end of the die block.

The press shown is of a well known type and, therefore, needs no specific description to make its structure and operation clear to those skilled in the art. It includes a bottom table 10 having a flat horizontal upper surface and four corner posts or rods 11 connected at their upper ends to the hydraulic piston cylinder 12. In the cylinder 12 there is a piston 13 having on its lower projecting end a plunger 14, and it will of course be understood that the plunger reciprocates vertically upon proper control of hydraulic power from any suitable source supplied to the cylinder 12.

The construction embodying the novel features of the present invention includes as one of its main elements a die block 15 having therein a vertical open end die chamber 16 and a channel or recess 17 in and extending across the lower end of said die block and across the lower end of chamber 16. The lower end surface of the die block 15 is flat and smooth and rests on the table 10 and has side flanges 18 through which bolts 19 pass to secure it in fixed position on the table. The die chamber 16 preferably has a lining 20 of suitable material as is common in the art and in the form shown is rectangular in cross section, although the invention is not limited to that particular form. The lower end of the chamber 16 is slightly flaring from the line 21 to the bottom, a distance equal to the length of the material compressed so that the compressed material may be easily ejected from its lower end. Below the chamber 16 and normally fitting its lower end walls, there is a movable die member 22 having, if desired, letters, figures, or other marking, engraved on its upper surface and having its lower surface inclined longitudinally of the channel 17. Its side surfaces make sliding engagement with

the walls of the upper portions of channel 17 and there is a fixed abutment or stop 23 carried by the die block projecting into channel 17 in such position that the inner 5 end of the die member 22 will make contact with it when that die member reaches proper position below chamber 16. Below the die member 22 there is a wedge member 24 serving as an operating and supporting member for said die member. It has a flat bottom surface slidably resting on table 10 and a portion 25 of its upper surface inclined longitudinally of the channel corresponding to the incline of the lower surface of the 10 die member and on which that die member rests. The said upper inclined portion is longer than the die member 22 and has fixed upwardly extending abutments 26 and 27 at the upper and lower ends of the inclined 15 surface 25 which serve to limit the relative longitudinal movement of said die member and wedge member. A coiled spring 28 makes contact at one end with the projection 27 and at its other end is pocketed in 20 a cylindrical socket 29 in the die member 22 and thus tends at all times to yieldingly force the die member down the inclined surface 25 towards projection 26 at the lower end of the wedge member. The wedge member 24 is guided in its longitudinal movement by side contact with the side walls of 25 channel 17 at its somewhat enlarged lower end portion.

Assuming that the parts of the mechanism heretofore described are in the position shown in Figures 1 and 2 and a block of compressed material is in the lower tapered portion of the die chamber 16 ready to be discharged, the operating or wedge member 40 24 is moved outwardly and during the first part of this movement the die member 22 does not move longitudinally with it but by reason of the pressure of spring 28 remains in contact with abutment 23 but as the inclined surface of the wedge member moves outwardly under it, the die member moves 45 downward by gravity on vertical lines until the end projection 26 on the wedge member engages it and positively carries it with the wedge member in the further outward movement. The result of this is that under one continuous outward movement of the operating wedge member the die member first moves downward a sufficient distance 50 to bring its upper surfaces below the plane of the lower surface of the compressed material and side edges of the chamber and that then it moves without obstruction or contact laterally from beneath the chamber to permit the compressed block to be freely 55 ejected. The compressed material in chamber 16 temporarily remains there by friction but is ejected by an operation of plunger 14 and it will be observed that the depth of 60 channel 17 and the consequent distance be-

tween its top wall to the table 10 is greater than the height of the compressed material so that when a compressed block is ejected, it drops to the table and may be moved laterally from it to a receptacle or chute (not shown) at one side. After the ejection of a compressed block, the return movement of the wedge member 24 carries the die member 22 with it until that die member strikes abutment 23 and its longitudinal movement is arrested and then further inward movement of the wedge member 24 will by the wedging action force the die member back up against the lower end of chamber 16 ready for the next compressing operation. During this reverse movement, the end of wedge member 24 carrying projection 26, strikes the previously ejected block and pushes it over to the edge of the table.

In the preferred embodiment of the invention shown, the operation is effected automatically by turning on and off hydraulic power. To this end the die block 15 has rigidly secured to it supporting and guiding rods 30 passing through and within the side flanges 18 of the die block parallel to the side walls of channel 17 and projecting a material distance therefrom. At their outer ends they are rigidly connected to a cross member 31. The wedge member 24 has at 90 its outer end integral laterally extending projections 32 in the form of a cross head slidably engaging said rods. Symmetrical rods 33 are rigidly secured at their outer ends to said projections 32 and extend into cylindrical piston chambers 34 of slightly greater diameter formed in die block 10 at the sides of and parallel to channel 17. The space around rods 33 at the outer ends of chambers 34 is closed by suitable water-tight means permitting sliding of said rods, and the piston chambers 34 are connected to any suitable hydraulic power generator by valve controlled pipes 35 and passageways 36.

The stationary cross member 31 has rigidly secured thereto at its center a pipe 37 which has an open end in a closed cylindrical socket 38 formed in the wedge member 24 parallel to the floor 10 and to the side wall of channel 17. A suitable water-tight closure 39 surrounds pipe 37 at the end of the socket 38 and the outer end of pipe 37 at the cross member 31 is connected to pipe 41 which in turn has free and open connection to a constant source of water under pressure. It will be observed that the constant hydraulic pressure in pipe 37 opening into chamber 38 will have a continuous and constant tendency to move the operating wedge member inwardly to the position shown in 115 Figure 1 but that when the connection is open from the source of hydraulic pressure to cylinders 34, the pressure acting on the wedge member 24 through the two rods 33 will overbalance the pressure effect from 120 125 130

pipe 37 in the opposite direction and that the result will, therefore, be to move the operating or wedge member outwardly, thus lowering the die member and moving it to one side. When the pressure in cylinders 34 is relieved, however, the continuous pressure in pipe 37 will be sufficient to automatically move the parts back to closed position. Owing to the difference in effective pressure 10 contact surfaces, the two rods 33 acting as pistons will of course over-balance in their effective action the reverse pressure on the end of the single pipe 37, even where the hydraulic pressure per inch is the same and 15 comes from the same source.

Having thus described my invention what is claimed as new and desired to be secured by Letters Patent is:

1. In a device of the class described, the combination of a stationary vertically arranged die chamber open at its ends, a plunger adapted to enter the upper end of said chamber and move downwardly therein, a movable bottom die member adapted to close 25 the lower end of said chamber, means operating through one continuous movement for moving said lower die member horizontally to position below the lower end of said chamber and then vertically against the lower end 30 of said chamber, closing it and operating through one continuous reverse movement to move said die member downwardly on vertical lines and then laterally to one side of the lower end of said chamber.

35 2. In a device of the class described, the combination of a stationary vertically arranged die chamber open at its ends, a plunger adapted to enter the upper end of said chamber and move downwardly therein, a movable die member closing the lower end of 40 said chamber, means operated by a constant source of power when connected thereto for moving said die member downwardly on vertical lines from said chamber and then laterally to one side of the vertical lines of said 45 chamber.

50 3. In a device of the class described, the combination of a stationary vertically arranged die chamber open at its ends, a plunger adapted to enter the upper end of said chamber and move downwardly therein, a movable die member closing the lower end of 55 said chamber, means operated by a constant source of power when connected thereto for moving said die member downwardly on vertical lines from said chamber and then laterally to one side of the vertical lines of said chamber, and automatic means operated by 60 constantly applied but yielding pressure for returning said die member to position below said chamber and then moving it upwardly into contact with the lower end of said chamber closing it when the source of power for said first mentioned moving means is cut off.

65 4. In a device of the class described, the

combination of a stationary vertically arranged die chamber open at its ends, a plunger adapted to enter the upper end of said chamber and move downwardly therein, a movable die member closing the lower end of 70 said chamber, controllable means operated by fluid under pressure for moving said die member downwardly on vertical lines and then laterally to one side of the vertical lines of said chamber as one continuous 75 operation and means operated by constantly applied fluid under pressure tending to cause a reverse movement of said die member laterally back to position beneath said chamber and then vertically into contact with the lower end of the chamber and to maintain it in that position, the relative pressures of the fluids and the structural relations of the operative parts being such that the force applied when the fluid under 80 pressure is connected to said first mentioned moving means will overbalance the force of the constantly applied fluid under pressure tending to cause the reverse movement.

5. In a device of the class described, the combination of a stationary vertically arranged die chamber open at its ends, a plunger adapted to enter the upper end of said chamber and move downwardly therein, a horizontal support a distance below the 95 lower end of said chamber greater than the height of the compressed material, a supporting and operating member adapted to slide across said support under said chamber from one side, a lower die member longitudinally movable with and on said supporting member with its upper surface normally slightly below the plane of the lower end of said chamber, the contact surfaces of said die member and supporting member being at a vertical incline to the line of movement, a fixed stop for interrupting the horizontal movement of said die member when it reaches a position below said chamber whereby the continued movement of 100 said supporting member will by the wedging action of the inclined contact surfaces force said die member vertically into close contact with the lower end of said chamber.

6. In a device of the class described, the combination of a stationary vertically arranged die chamber open at its ends, a plunger adapted to enter the upper end of said chamber and move downwardly therein, a horizontal support a distance below the 115 lower end of said chamber greater than the height of the compressed material, a supporting and operating member adapted to slide across said support under said chamber from one side, a lower die member longitudinally movable with and on said supporting member with its upper surface normally slightly below the plane of the lower end of said chamber, the contact surfaces of said die member and supporting member 120

being at a vertical incline to the line of movement, a fixed stop for interrupting the horizontal movement of said die member when it reaches a position below said chamber whereby the continued movement of said supporting member will by the wedging action of the inclined contact surfaces force said die member vertically into close contact with the lower end of said chamber, 10 a fixed stop at the lower end of the inclined surface of said supporting and operating member in the path of said die member and yielding means connecting said die member and supporting member tending to force 15 said die member longitudinally toward said fixed stop.

7. In a device of the class described, the combination of a stationary vertically arranged die chamber open at its ends, a plunger adapted to enter the upper end of said chamber and move downwardly therein, a horizontal support a distance below the lower end of said chamber greater than the height of the compressed material, a supporting and operating member adapted to slide across said support under said chamber from one side, a lower die member longitudinally movable with and on said supporting member with its upper surface 30 normally slightly below the plane of the lower end of said chamber, the contact surfaces of said die member and supporting member being at a vertical incline to the line of movement; a fixed stop for interrupting the horizontal movement of said die member when it reaches a position below said chamber whereby the continued movement of said supporting member will by the wedging action of the inclined contact surfaces force said die member vertically into close contact with the lower end of said chamber, fixed vertically projecting stops at the upper and lower ends of the inclined surface of said supporting member in the 40 path of the die member, and a coiled spring abutting at one end the projecting stop at the upper end of said inclined portion and pocketed at its other end in said die member.

8. In a device of the class described, the combination of a stationary vertically arranged die chamber open at its ends, a plunger adapted to enter the upper end of said chamber and move downwardly therein, a movable bottom die member adapted to 50 close the lower end of said chamber, an operating member movable on fixed straight lines for moving said die member to and from position below said chamber and for moving it vertically into and out of contact 55 with the lower end of said chamber, stationary guiding means for said operating member, fixed rods carried by said operating member parallel to its line of movement, stationary parts having piston chambers entered by said rods, liquid-tight closures for 60

the ends of said piston chambers around said rods, and means for supplying a liquid under pressure to said piston chambers to move said operating member in one direction.

9. In a device of the class described, the combination of a stationary vertically arranged die chamber open at its ends, a plunger adapted to enter the upper end of said chamber and move downwardly therein, a movable bottom die member adapted to 70 close the lower end of said chamber, an operating member movable on fixed straight lines for moving said die member to and from position below said chamber and for moving it vertically into and out of contact with the lower end of said chamber, stationary guiding means for said operating member, fixed rods carried by said operating member parallel to its line of movement, stationary parts having piston chambers entered by said rods, liquid-tight closures for the 75 ends of said piston chambers around said rods and means for supplying a liquid under pressure to said piston chambers to move said operating member in one direction and yielding but constantly acting means tending to move said operating means in the reverse direction with a force less than that imparted by the liquid under pressure in 80 said pistons. 90

10. In a device of the class described, the combination of a stationary vertically arranged die chamber open at its ends, a plunger adapted to enter the upper end of said chamber and move downwardly 100 therein, a horizontal support a distance below the lower end of said chamber greater than the height of the compressed material, a supporting and operating member adapted to slide across said support under said chamber from one side, a lower die member longitudinally movable with and on said supporting member with its upper surface normally slightly below the plane of the lower end of said chamber, the contact surfaces of said die member and supporting member being at a vertical incline to the line of movement, a fixed stop for interrupting the horizontal movement of said die member when it reaches a position below said chamber whereby the continued movement of said supporting member will by the wedging action of the inclined contact surfaces force said die member vertically into close contact with the lower end of said chamber, fixed vertically projecting stops at the upper and lower ends of the inclined surface of said supporting member in the path of the die member, and a coiled spring abutting at one end the projecting stop at the upper end of said inclined portion and pocketed at its other end in said die member, said operating member having therein a piston chamber in the line of movement, a stationary tube entering 110 120 130

said last-mentioned chamber, a liquid-tight closure in the end of said chamber around said tube, and means for constantly supplying liquid under pressure to said tube tending to move said operating member in the reverse direction.

11. In a device of the class described the combination with a hydraulic press having a reciprocating plunger and a stationary table below said plunger, a die block resting on and rigidly secured to said table having therein an open end chamber adapted to be entered by said plunger and a transverse channel or recess in its lower end across the lower end of said chamber the upper surface of which channel is a distance above the table slightly greater than the height of compressed material, an operating wedge member slidable on said floor in said channel across the lower end of said chamber guided by lateral contact with the walls of said channel, a bottom die member on and movable with said wedge member having a bottom surface on an incline corresponding to that of the wedge member, means for yieldingly holding said die member on the lower portion of said wedge member with its upper surface slightly below the bottom of said chamber and means for stopping the inward movement of said die member when it reaches a position directly below said chamber.

12. A die mechanism for presses comprising in combination a die block adapted to rest on and be secured to the table of the press having therein an open end die chamber and a transverse recess or channel across the lower end of said chamber having a depth slightly greater than the height of the material compressed, a wedge block laterally fitting and longitudinally movable in the lower end of said channel with its lower surface in the plane of the end of said die block, a bottom die member laterally fitting said channel mounted on and movable with and, to a limited extent, longitudinally on said wedge member, yielding means for normally retaining said die member on the forward lower portion of the wedge member, and fixed means on said die block for interrupting the movement of said die member when below said chamber.

13. A die mechanism for presses comprising in combination a die block adapted to rest on and be secured to the table of the press having therein an open end die chamber and a transverse recess or channel across the lower end of said chamber having a depth slightly greater than the height of the material compressed, a wedge block laterally fitting and longitudinally movable in the lower end of said channel with its lower surface in the plane of the end of said die block, a bottom die member laterally fitting said channel mounted on and movable with

and, to a limited extent, longitudinal on said wedge member, yielding means for normally retaining said die member on the forward lower portion of the wedge member, and fixed means on said die block for interrupting the movement of said die member when below said chamber, supporting guide rods rigidly secured to said die block on opposite sides of said channel parallel to its side walls and projecting a material distance from it, lateral projections on the outer end of said wedge member making sliding engagement with said rods, plungers secured at their outer ends to said lateral projections and entering piston chambers in said die block at their inner ends, water-tight closures at the ends of said piston chambers around said plungers, and means for supplying fluid under pressure to said piston chambers.

14. A die mechanism for presses comprising in combination a die block adapted to rest on and be secured to the table of the press having therein an open end die chamber and a transverse recess or channel across the lower end of said chamber having a depth slightly greater than the height of the material compressed, a wedge block laterally fitting and longitudinally movable in the lower end of said channel with its lower surface in the plane of the end of said die block, a bottom die member laterally fitting said channel mounted on and movable with and, to a limited extent, longitudinally on said wedge member, yielding means for normally retaining said die member on the forward lower portion of the wedge member, and fixed means on said die block for interrupting the movement of said die member when below said chamber, supporting guide rods rigidly secured to said die block on opposite sides of said channel parallel to its side walls and projecting a material distance from it, lateral projections on the outer end of said wedge member making sliding engagement with said rods, plungers secured at their outer ends to said lateral projections and entering piston chambers in said die block at their inner ends, water-tight closures at the ends of said piston chambers around said plungers, and means for supplying fluid under pressure to said piston chambers, a stationary yoke rigidly connected to the outer ends of said guide rods, a fluid pressure pipe connected to said yoke and extending parallel to the guide rods into a piston chamber in said wedge member, and a water-tight closure for said last mentioned chamber around said pipe.

15. A die mechanism for presses comprising in combination a die block adapted to rest on and be secured to the table of the press having therein an open end die chamber and a transverse recess or channel across the lower end of said chamber having a depth slightly greater than the height of

the material compressed, a movable bottom die member, an operating member movable in said channel from one end for moving said die member to and from position below said chamber and vertically into or out of contact with the lower end of said chamber, means for guiding and moving said operating member comprising interengaging fixed

parts carried by said die block and wedge member having relative sliding movement 10 and means carried by said die block for causing said relative movement through hydraulic power.

In testimony whereof I hereunto affix my signature.

JAMES PATRICK MADDEN.
